UNITED STATES PATENT OFFICE.

FRANK X. MUDD, OF CHICAGO, ILLINOIS.

CUFF.

SPECIFICATION forming part of Letters Patent No. 745,644, dated December 1, 1903.

Application filed May 8, 1903. Serial No. 156,156. (No model.)

To all whom it may concern:

Be it known that I, FRANK X. MUDD, a citizen of the United States, residing at Chicago, in the county of Cook and State of Illinois, have invented a new and useful Improvement 5 in Cuffs, of which the following is a specification.

My invention relates particularly to reversible link-button cuffs; and my primary object 10 is to render reversible link-button cuffs of the type now in most common use—viz., those employing a tab at one end for connection with the cuff-holder or with the button of the wristband of the shirt.

15 The invention is illustrated in the accompanying drawings, in which—

Figure 1 represents a perspective view of my improved cuff and a portion of a shirt-sleeve with which it is connected; Fig. 2, a 20 plan view of the cuff; Fig. 3, a broken sectional view at the link-button, taken as indicated at line 3 of Fig. 1; and Fig. 4, a broken sectional view at the wristband-button, taken as indicated at line 4 of Fig. 1.

25 A represents a cuff having upper and lower edges a and lateral edges a' . The cuff is provided at its four corners with buttonholes a^2 . Projecting from one of the edges a' of the cuff are tabs or ears a^3 , located near the 30 upper and lower edges of the cuff and having buttonholes a^4 in alignment with the respective sets of buttonholes a^2 .

35 B represents a shirt-sleeve having a wristband b equipped with a button b' , by means of which the cuff is secured at one end to the sleeve in the usual manner.

The link-button b^2 is inserted at the free

end of the cuff, extending through one buttonhole a^2 , then through the corresponding buttonhole a^4 , and then through the other 40 corresponding buttonhole a^2 .

Obviously it is a matter of indifference which end of the cuff is presented, since it is perfectly symmetrical with relation to a central transverse plane perpendicular to the 45 cuff, as it appears in Fig. 1.

The gist of the invention lies in the provision of the buttonholes adjacent to the tabs and in alinement with the buttonholes of the duplicate tabs and the buttonholes at the opposite edge of the cuff.

While it is preferred to arrange both tabs at the same lateral edge of the cuff, this arrangement may be departed from without departure from the gist of the invention, so 55 long as the upper and lower lateral tabs and two rows of buttonholes with three buttonholes in each row are retained.

What I regard as new, and desire to secure 60 by Letters Patent, is—

A reversible cuff for link-buttons having a body portion provided near each of its four corners with a buttonhole, and two tabs fixedly attached to one end of said body portion said tabs each having a buttonhole in longitudinal alinement with the adjacent hole in the body portion and adapted to be folded to be interposed between the meeting ends of the folded cuff.

FRANK X. MUDD.
